UNITED STATES PATENT OFFICE.

PAUL M. KREE, OF NEW YORK, N. Y., AND FERNAND DAUTEUIL, OF DUMONT, NEW JERSEY.

AUTOMATIC STOP AND START FOR PHONOGRAHS.

Application filed August 25, 1922. Serial No. 584,294.

To all whom it may concern:

We, PAUL M. KREE and FERNAND DAUTEUIL, citizens of the United States, and of the Republic of France, respectively, and residents of the city, county, and State of New York, and of Dumont, Bergen County, and State of New Jersey, respectively, have invented a new and Improved Automatic Stop and Start for Phonographs, 10 of which the following is a full, clear, and exact description.

Our invention relates to a mechanism for automatically starting and stopping the movement of a phonograph turn-table and 15 it has reference more particularly to a device comprising an electromagnetic mechanism, for operating the brake of a turn-table when the end of a record groove has been reached, and to release the brake from the 20 turn-table when the tone arm is moved to the starting position to play the record.

It is also an object of this invention to provide a device that can easily be attached to any phonograph on the market.

25 A practical embodiment of our invention is illustrated in the accompanying drawings, forming part of the specification, in which similar characters of reference indicate corresponding parts in all the views.

30 Figure 1 is a fragmentary top plan view of a phonograph equipped with our device.

Figure 2 is a plan view of the electromagnetic mechanism and its housing, the cover 35 being removed, showing the relative position of the different parts.

Figure 3 is a section on line 3—3, Figure 1, and

40 Figure 4 is an electrical diagram showing the circuits of the device.

Referring to the drawings, 5 is the phonograph cabinet, the motor shaft 6 of which being only shown as the necessary part for illustrating the invention. The motor shaft 45 6 carries the customary turn-table 7, which is adapted to receive a record 8. The said record 8 carries a metallic washer 9, which may be attached thereto by the manufacturer, or, by the record owner subsequently, if 50 so desired. This washer may serve as a label for the record.

The washer 9 fits the shaft 6 snugly, for the purpose of establishing an electrical contact between the two, the necessity of 55 which will be seen hereafter.

The brake-shoe 10 is attached to a bar 11, mounted to slide in suitable bearings 11', provided in the housing 12, of the electromagnetic mechanism. The housing has suitable means 13, whereby it can easily be 60 attached to the cabinet 5 of the phonograph. The bar 11, carries an iron platen 14, disposed transversely of said bar, and faced on each side by electromagnets 15 and 16 respectively.

65 The electromagnets 15 serve to move the shoe 10 against the turn-table 7 of the phonograph while the electromagnets 16 act to disengage the shoe 10 from the turn-table 7. The platen 14 carries on each side 70 thereof contacts 17 and 18 respectively. The contact 17 is adapted to engage a corresponding contact member 19, when the platen 14 is attracted by the electromagnets 15, as illustrated in Figure 2. The contact 75 member 18 is adapted to engage a corresponding contact member 20 when the platen 14 is attracted by the electromagnets 16, and, as shown in the drawings, when the contacts 17 and 19 are engaged the contacts 80 18 and 20 are disengaged, and vice versa.

The tone arm 21 of the phonograph, is provided with an extension 22 which may be attached thereto in any suitable way. The said arm extends into a fork formed of a 85 metallic member 23 and an insulating member 24, both forming a unit which is mounted on a pivot 25, said pivot being supported on a suitable bracket 26 extending from the cabinet 5.

90 The contact point 20 is connected by a suitable conductor 27 to the motor of the phonograph, and, in consequence to the shaft 6 and therefore to the washer 9. The contact point 18, on the other hand, is connected to the 95 electromagnets 15. The electromagnets 15 are in turn connected to one pole of a battery 28, by a conductor 29, (see Figure 4), the other pole of the battery being connected by a conduit 30 to the tone arm.

100 When the needle 31 of the reproducer 32 of the tone arm comes in contact with the washer 9, a circuit to the electromagnets 15 will be closed, as will be seen from Figure 4, and the slide bar 11 will move towards the 105 table 7 and apply the brake and therefore stop the rotation of the turn-table. The movement of the platen 14 will disengage the contacts 18 and 20, while the contacts 17 and 19 will be engaged.

- It will be remarked that when the tone arm is swinging towards the center of the turn-table, the extension 22 engages the insulating member 24 of the fork. When the tone arm 21 is swung to the outer periphery of the turn-table, the extension 22 will swing away from the insulating member 24 to engage the metallic member 23, before the fork will swing on its pivot 25.
- 10 The metallic member 23 is connected by a conductor 33, to the contact 19, while the contact 17 is connected to one end of the electromagnets 16 and the other end of said electromagnets is connected to the same pole 15 of the battery to which the electromagnets 15 are connected. As the extension 22 engages the metallic member 23, the circuit is closed to the electromagnets 16, as will be seen from Figure 4, and, in consequence, 20 the slide bar 11 will be drawn away from the turn-table 7, thereby releasing the turn-table and permitting the motor of the photograph to rotate the same.

From the above description it will be seen that our device will automatically stop and start the rotation of the turn-table and that the electric current is only used for a fraction of the movement, when the brake is either applied to or removed from the turn-table. In other words, a person cannot, by inadvertence, leave the apparatus so that the source of energy could be exhausted and thereby render the device inoperable.

We claim:

- 35 1. In combination with a talking machine having a turn-table, brake means for same and a tone arm having reproducing means, electromagnetic means for moving the brake mechanism to engage the turn-table, electromagnetic means for moving the brake away 40 from the turn-table, an open circuit for said electromagnetic means, means for closing the circuit to the electromagnetic means for moving the brake away 45 from the turn-table, operable by the outward movement of the tone arm, and means adapted to be provided on a record to be engaged by the reproducing means of the tone arm, to close the circuit to the electromagnetic means for applying the brake to the turn-table.
2. In combination with a talking machine having a turn-table, brake means for same, and a tone arm having reproducing means, 55 means for moving the brake away from the turn-table, electromagnetic means for moving the said brake into engagement with the turn-table, an open circuit for said electromagnetic means, an open switch in said circuit, adapted to be closed by said means for 60 moving the brake from the turn-table, and means adapted to be provided on the record to be engaged by the reproducing means of

the tone arm, for closing the circuit to the electromagnetic means, whereby said electromagnetic means will move the brake into engagement with the turn-table, substantially as and for the purpose set forth.

3. In combination with a talking machine having a turn-table, brake means for same and a tone arm having reproducing means, electromagnetic means for moving the brake means into engagement with the turn-table, a second electromagnetic means for moving the brake means away from the turn-table, an open circuit for said electromagnetic means, an open switch in the circuit of the first electromagnetic means adapted to be closed by said second electromagnetic means, when a current flows therethrough, an open switch in the circuit of the second electromagnetic means adapted to be closed by the first electromagnetic means when a current flows therethrough, means for closing a circuit to the second electromagnetic means, becoming operable by the outward movement of the tone arm, and means adapted to be provided on a record and adapted to be engaged by the reproducing means of the tone arm on its inward movement for closing the circuit to said first electromagnetic means, substantially as and for the purposes set forth.

4. In combination with a talking machine having a turn-table, brake means for same and a tone arm having reproducing means, electromagnetic means for moving the brake means into engagement with the turn-table, second electromagnetic means for moving the brake means away from the turn-table, an open circuit for said electromagnetic means, an open switch in the circuit of the first electromagnetic means, adapted to be closed when the second electromagnetic means is energized, an open switch in the open circuit of the second electromagnetic means, adapted to be closed when the first electromagnetic means is energized, a fork having an electroconducting branch and an electroinsulated branch, means carried by the tone arm adapted to engage the said member of the fork, said tone arm and fork being in the open circuit of the second electromagnetic means, and means adapted to be provided on the record to be engaged by the reproducing means of the tone arm to close the circuit to said first electromagnetic means, said means on the record and electroconducting means on the fork being so related that when the reproducing means engage the means on the record, the tone arm is disconnected from the electroconducting member of the fork.

FERNAND DAUTEUIL.
